[57] CLAIM

The ornamental design for a slide-mount shelf, as shown and described.

DESCRIPTION

FIG. 1 is a top left perspective view of a slide-mount shelf showing my new design;

FIG. 2 is a top rear perspective view thereof;

FIG. 3 is a top plan view thereof;

FIG. 4 is a front perspective view thereof, as seen from the top left;

FIG. 5 is a rear perspective view thereof, as seen from the top right rear; and,

FIG. 6 is a front perspective view thereof, as seen from the top, the undisclosed opposite bottom perspective view being a mirror image.
